UNITED STATES PATENT OFFICE.

LOUIS W. SOUTHGATE, OF WORCESTER, MASSACHUSETTS, ASSIGNOR TO THE
OTIS ELEVATOR COMPANY, OF EAST ORANGE, NEW JERSEY.

ELEVATOR-CONTROLLER.

SPECIFICATION forming part of Letters Patent No. 657,465, dated September 4, 1900.

Application filed November 13, 1896. Renewed January 14, 1899. Serial No. 702,189. (No model.)

To all whom it may concern:

Be it known that I, LOUIS W. SOUTHGATE, a citizen of the United States, residing at Worcester, in the county of Worcester and 5 State of Massachusetts, have invented a new and useful Improvement in Elevator-Controllers, of which the following is a specification.

The aim of this invention is to improve that class of elevator-controllers in which a controlling rope or ropes is or are connected to the elevator-car to travel therewith, a controlling-rope of this character being commonly termed a "running" controlling-rope.

The common or ordinary way to arrange a 15 running controlling-rope is to attach both ends thereof to the car or one end thereof to the car and the other end to a weight which moves up and down with the car. My arrangement consists in attaching the controlling rope or ropes to the elevator-car, in using a take-up device for taking up or letting out the controlling rope or ropes as the car travels, and in applying motor-controlling connections to said controlling rope or ropes between the car and said take-up device. By 25 applying the motor-controlling connections in this manner between the car and the take-up device a very efficient mechanism is provided, because the running controlling rope or ropes 30 pass directly from the car to said connections. Also by this construction a very short length of controlling-rope can be used and all overhead work in the elevator-well for the controlling rope or ropes can be done away with.

35 In the preferred form of my invention the take-up device consists of sets of stationary and movable devices operating with the stationary and movable sheaves of one of the ordinary forms of hydraulic motors. The motor-controlling connections consist of a pulley or pulleys around which the running controlling rope or ropes is or are passed, said pulley or pulleys being mounted on a pivoted lever or arm, from which extend connections 40 to the motor-controlling element. By the term "motor-controlling element" I mean the main or supplemental valve of a hydraulic engine, the rheostat or similar device of an electric motor, or any equivalent device that

45 is used to start, stop, or reverse the mechanism that raises and lowers the car. Also by

my construction I can attach the other end of the controlling rope or ropes to a fixed point and can there use any ordinary adjusting or tensioning device.

55

I will now describe my invention in detail, and reference, to follow this description, should be had to the accompanying two sheets of drawings, in which—

Figure 1 is a side elevation of an elevator 60 and motor arranged according to my invention. Fig. 2 is a plan of the motor and sheaves. Fig. 3 is a side elevation of a modification. Fig. 4 is a plan of the hoisting-drum and take-up device used in the modification shown in 65 Fig. 3; and Fig. 5 is a view similar to Fig. 1, illustrating how my invention can be carried out with a single running controlling-rope.

Referring to the first sheet of drawings, A designates the elevator-car, and C the hoisting-cables, which are led over the ordinary overhead sheaves B and then down to the bottom of the well around a set of stationary sheaves D and a set of traveling sheaves E, which latter are mounted in a carriage F, 70 which carriage is actuated by means of a piston-rod extending into and connected to a piston moving in the cylinder G. Water is let into and out of the cylinder G by means of any of the usual valves V. This arrangement is a common one and is well understood.

Mounted on or carried by the car are any of the usual operating devices for a controlling rope or ropes. In the specific illustration shown the same consists of a lever 10, 85 rigidly secured upon a shaft 11, which shaft is journaled in brackets secured to the bottom of the car, and also mounted on this shaft 11 is a lever 12.

13 and 14 designate two running controlling-ropes. Each of these ropes is rigidly connected at one of its ends to the lever 12. The controlling-rope 13 then passes down over pulleys 15 and 23, and the controlling-rope 14 passes down around pulleys 16 and 22. 95 The pulleys 15 and 16 are mounted on a lever 17, which is rigidly secured on the shaft 18, extending from which shaft is an arm 19, which connects by link 20 to a bell-crank lever 21, which latter connects to the valve-stem. The pulleys or sheaves 22 and 23 are journaled on fixed bearings. From these

pulleys the controlling-ropes 13 and 14 pass back around a set of sheaves 24, mounted on a shaft 25. One convenient way to arrange this set of sheaves is to mount the shaft 25 in brackets bolted on top of the cylinder G. The carriage F is extended up, as shown, and has rigidly secured therein a shaft 26, upon which are mounted a number of sheaves 27, which I call "movable" sheaves. The controlling-ropes 13 and 14 are led back and forth around these sheaves 24 and 27 in substantially the same manner that the controlling-ropes are passed back and forth between the sheaves D and E, as many sheaves 24 and 27 being used as there are sheaves D and E. The running controlling-ropes 13 and 14 pass first to one of the sheaves 24, then back to the sheaves 27, and then back and forth around these sheaves. Secured to the ends of the controlling-ropes are bolts or screw-eyes 28, which pass through brackets 29, which may be secured to the top of the cylinder G and which have adjusting-nuts 30. By this means the tension of the controlling-ropes can be adjusted. I intend in some cases to use at this point any of the ordinary tension take-up devices, which are well known in the art. It will be seen that by this construction as the car moves upwardly the sheaves 27 will move to the right, and hence the running controlling-ropes 13 and 14 will be let out. As the car descends the sheaves 27 will move to the left, and then the running controlling-ropes will be taken up. This paying out or taking up of the controlling-ropes will exactly correspond to the movement of the car. Hence if the lever 10 is operated the valve will be properly manipulated through the connections referred to. This forms a very neat simple device for the purpose.

The running controlling-ropes can be easily adjusted. A very short length of controlling-rope is required. No overhead work for the controlling-ropes is required in the elevator-well, and the take-up device is located adjacent to the motor and is very accessible for adjustment and repair. It will also be seen that the motor-controlling element will be very easily and accurately operated from the operating device carried by the car, as the pull therefrom will be transmitted directly by the ropes 13 and 14 to the pulleys 15 and 16 and from the pulleys 15 and 16 directly to the motor-controlling element.

In Figs. 3 and 4 I have shown a modified form of motor and take-up device. In this modification an electric motor J is used to actuate a winding-up drum H for the hoisting-cables C, the motor being arranged to operate the same through the usual worm and worm-wheel W. The hoisting-drum is represented as being mounted upon a shaft 31. Also arranged on this shaft 31 is a winding-drum I, to which the controlling-ropes 13 and 14 pass from the pulleys 22 and 23, the controlling-ropes being led to their drum I in a direction opposite to that which the control-

ling-cables pass to their drum H, so that as the hoisting-cables are taken up to lift the car the controlling-ropes will be paid out, and vice versa. The drums H and I are preferably made of the same size or in any event to turn at the same peripheral speed. In this modification the link 20 is shown as connected to a pivoted lever 32, which may operate any of the ordinary rheostats 33 for controlling the electric motor J.

In Fig. 5 I have shown a structure similar to that shown in Fig. 1, except that one controlling-rope 13 is used, the lever 12 being provided with a weight 34, which will act to keep the running controlling-rope 13 taut, and the lever 17 being provided with a similar weight 35, which is connected thereto by a flexible connection passing over a fixed sheave 36. This arrangement is such that the two weights 34 and 35 will substantially counterbalance. This construction is preferably only used in buildings of comparatively low height, where the weight of the running controlling-rope may be neglected. The preferred construction is, however, to use two running controlling-ropes or a double strand attached to the car, as with this construction the weight of the two ropes or strands will counterbalance each other.

The details herein shown and described may be greatly varied by a skilled mechanic without departing from the scope of my invention as expressed in the claims.

Having thus fully described my invention, what I claim, and desire to secure by Letters Patent, is—

1. The combination of an elevator-car and its motor, a running controlling-rope, a positively-actuated take-up device for taking up or letting out the controlling-rope as the car travels, and motor-controlling connections engaging the controlling-rope between the car and the take-up device, substantially as described.

2. The combination of an elevator-car and its motor, two running controlling-ropes, a positively-actuated take-up device for taking up or letting out said controlling-ropes as the car travels, and motor-controlling connections engaging said controlling-ropes between the car and the take-up device, substantially as described.

3. The combination of an elevator-car and its motor, a running controlling-rope attached at its ends to the car and a fixed point respectively, motor-controlling connections and a take-up device applied to said rope between the motor-controlling connections and the fixed point, substantially as described.

4. The combination of an elevator-car and its motor, running controlling-ropes attached to the car and to fixed points respectively, motor-controlling connections, and a take-up device applied to said ropes between the motor-controlling connections and the fixed points, substantially as described.

5. The combination of an elevator-car and

its motor; a running controlling-rope attached to an operating device carried by the car, a pulley as 15 to which said running controlling-rope passes from the operating device, 5 connections from this pulley 15 to the motor-controlling element, and a positively-actuated take-up device for taking up or letting out said rope as the car travels, to which said controlling-rope passes from the pulley 15, substantially as described.

6. The combination of an elevator-car and its motor, two running controlling-ropes connected to an operating device carried by the car, pulleys as 15 and 16 around which said 15 ropes pass from said operating device, connections from said pulleys to the motor-controlling element, and a positively-actuated

take-up device to which said ropes pass from said pulleys, substantially as described.

7. The combination of an elevator-car and its motor, motor-controlling connections, a running controlling-rope extending in a straight line from the elevator-car to the motor-controlling connections, and means for maintaining a constant tension of the controlling-rope as the car moves up and down, substantially as described.

In testimony whereof I have hereunto set my hand in the presence of two subscribing witnesses.
